VEST CHAIN OR SIMILAR ARTICLE

John W. Wolfenden, Attleboro, Mass.

Application January 6, 1950, Serial No. 7,049

Term of patent 3½ years

(Cl. D45—16)

To all whom it may concern:

Be it known that I, John W. Wolfenden, a citizen of the United States, residing at Attleboro, in the county of Bristol and Commonwealth of Massachusetts, have invented a new, original, and ornamental Design for Vest Chain or Similar Article, of which the following is a specification, reference being had to the accompanying drawing, forming part thereof.

In the drawings,

Fig. 1 is a front elevational view of a vest chain showing my new design; and

Fig. 2 is an edge elevational view thereof.

I claim:

The ornamental design for a vest chain or similar article, as shown.

JOHN W. WOLFENDEN.
